UNITED STATES PATENT OFFICE.

RICHARD BRADSHAW, OF MONTREAL, QUEBEC, CANADA.

SPRING MATTRESS-FRAME.

1,360,173.

Specification of Letters Patent. Patented Nov. 23, 1920.

Application filed February 10, 1919. Serial No. 275,997.

To all whom it may concern:

Be it known that I, RICHARD BRADSHAW, a subject of the King of Great Britain, and resident of the city of Montreal, in the Province of Quebec and Dominion of Canada, have invented certain new and useful Improvements in Spring Mattress-Frames, of which the following is a full, clear, and exact description.

10 This invention relates to improvements in spring mattress frames, and the object of the invention is to provide a mattress frame which will be absolutely rigid and will not twist or buckle.

15 A further object is to provide a mattress frame which may be very cheaply and easily manufactured.

At the present time, metallic spring mattress frames are largely in demand and owing to the small dimensions of the end rails, it has been found necessary to set the side rails considerably below the end rails, in order to keep them clear of the fabric. This has usually been accomplished by connecting the end and side rails together by means of malleable cast brackets. Owing to the small dimensions of the members, considerable difficulty has been experienced in getting rigid joints, with the result that 20 the frames twist considerably, that is to say, if a metallic mattress frame is laid on the floor, one corner may be lifted a considerable distance before any of the other three corners leave the floor. In some cases, this 25 may be as much as twelve or fifteen or more inches. This inherent weakness of the frame subjects it to great stresses in handling, which it is not designed to withstand and which result in its early destruction.

40 According to the present invention, the connecting brackets are entirely eliminated and additional braces are provided, which so stiffen the frame that it becomes absolutely rigid and when subjected to the test mentioned above will not yield in any one corner more than a fraction of an inch. According to this invention, the side rails of the frame are tubular and are offset adjacent the ends, as clearly shown, so as to bring the central portion of the side rails entirely out of the plane of the end rail. Cross braces of tube or rod are connected between the side rails, preferably by means of chilled castings, which may also be used 45 to support the entire frame upon the bedstead, thus enabling the side rails to act in

a restricted manner as semi-elliptic springs when the bottom fabric is tensioned by weight placed on it. The side rails are secured directly to the end rails, thus facilitating and cheapening the construction. 60

In the drawings which illustrate the invention;—

Figure 1 is a perspective view of the frame. 65

Fig. 2 is a fragmentary sectional view illustrating one method of attaching the side and end rails.

Fig. 3 is a view similar to Fig. 2, illustrating another method of attachment. 70

Fig. 4 is another sectional view illustrating the attachment of the side rails and cross braces.

Referring more particularly to the drawings, 11 designates the end rails of a spring mattress frame, which are preferably of angle section, and 12 the longitudinal or side rails of the frame, which are preferably tubular. The side rails are offset adjacent their ends, as clearly shown at 13, so as to bring the ends into line some distance out of the line of the central portion. The side and end rails are connected preferably by means of cups 14 secured to the end rails, into which the ends of the side rails fit. 75 80 85

These cups may be secured to the end rails in any suitable manner, such as by a rivet 15 shown in Fig. 2 or an electric weld 16 shown in Fig. 3. It is obvious that if the head of the rivet 15 is enlarged and fits 90 snugly within the side rail, the cup 14 may be dispensed with. Cross braces 17 are located between the side rails at approximately the ends of the straight central portions, as clearly shown in Fig. 1. It will 95 be noted that these cross braces are some distance from the end rails and are in an entirely different horizontal plane. The cross braces are preferably connected to the end rails by chilled castings 18 in the manner 100 well known to manufacturers of metal beds. These castings 18 may each be provided with an outwardly projecting lug 19, which will serve to support the frame upon a bedstead. It will thus be seen that the support of the 105 frame is removed some distance from the ends. The lines 20 indicate the margins of a bed bottom fabric stretched between the end rails 11.

The location of the cross braces 17 in a 110 different plane from the end rails 11 and the offsetting of the side rails to connect all to-

gether forms the frame into what may be described roughly as the skeleton of a rectangular solid, and it is due to this that the structure has great rigidity. In other words, a frame constructed according to this invention has thickness or depth as well as length and breadth, whereas the mattress frames heretofore constructed have only length and breadth. The fact that the side 10 rails are ordinarily located in a plane below the end rails does not give depth or thickness to the structure, for the reason that there is no cross connection at the lower level and the offsetting therefore serves merely 15 to give greater flexibility to the structure.

When the frame is in use, it is supported at points remote from the ends, thus leaving a certain length of the side rails between the points of support and the end rails, which 20 portions of the side rails will naturally flex slightly when the end rails tend to approach one another by reason of a load on the bottom fabric. This spring or yield of the side rails has no more destructive influence 25 on the frame than the flexing of a semi-ellip-

tic spring, whereas the same tendency of the end rails to approach in a frame built up by means of brackets has a very destructive effect. It will also be noticed that the cross braces 17 render the side rails mutually supporting against side sway, whereas in the ordinary construction there is no such support. 30

Having thus described my invention, what I claim is:—

A mattress frame comprising end members, cup-shaped socket members having the bottom walls thereof secured to said end members, side members of uniform cross section from end to end offset a short distance 40 from the ends thereof to provide aligned end portions disposed in a different plane from the central portion and extending into said sockets to connect the end members together, and transverse members rigidly connecting 45 the side members between the offsets thereof.

In witness whereof, I have hereunto set my hand.

RICHARD BRADSHAW.
